SPOOL AND TUBE APPLICABLE THERETO

Edward T. Allan, Cincinnati, Ohio

Application December 14, 1936, Serial No. 115,749

16 Claims. (Cl. 242—121)

I have exemplified my invention as employed in single head spools arranged to have comparatively large quantities of thread wound thereon, used principally in power sewing machines, and 5 for wrapping. The term thread as used includes string. It is, of course, applicable in other relations.

Single head spools have heretofore been usually made of wood, paper or fibre as integral structures, comprising a tubular portion formed as an integral closed tube and an integral conical head integral with the tube. The spools as heretofore made have been bulky, heavy and weak, were expensive to manufacture, and were adversely affected by climatic changes both before and after 10 winding the thread thereon, and required considerable space in transporting and in storing the same. In damp weather such spools were subject to warping and becoming porous, and the 15 heads thereof were subject to breaking and of being broken and stripped from the tubes there- 20 of due to the pressure of the thread wound on the spool.

It is the object of my invention to provide a 25 new and improved spool free of the objections stated; further, to provide a new and improved spool in which the tube and the head are separable; further, to so connect the head and the tube that tubes of different lengths may be associated with a head; further, to provide new and 30 improved spools in which the tubes and the heads are interchangeable; further, to provide a tube, the longitudinal margins of the body of which are arranged in lapping relation in such 35 manner that the tube may be enlarged in cross-sectional dimension; and, further, to provide the coacting margins of said tubing with complementary slots and laterally acting shoulders to permit lapping of said margins and to restrict 40 contraction of the tube in cross-sectional dimensions to a predetermined minimum.

It is the object of my invention, further, to 45 provide a tube with releasable connecting means coacting with the wall of a central hole in the head of the spool whereby to releasably connect the tube and the head in manner to resist outward endwise release between the head and the tube and to permit assembling and disassembling between the tube and the head in the opposite 50 site direction; further, to provide the tube of the spool with means along the length thereof for holding the thread in position lengthwise of the tube; and, further, to provide spools which are light, strong and durable, and which occupy little 55 space, and the parts whereof may be separated

for nesting the same or a portion thereof for storage and shipment.

My invention consists in novel means for accomplishing the respective objects stated; and, further, in the novel parts and the novel structures, arrangements and combinations of parts hereinafter described.

In the drawings:

Fig. 1 is a side elevation of a portion of a winding machine, the horizontal spindle whereof has a spool embodying my invention mounted thereon, the spool being partly wound, and the size of the fully wound spool being indicated in dotted lines.

Fig. 2 is a longitudinal section of the same, taken on the line 2—2 of Fig. 1, partly broken away, and with the thread removed.

Fig. 3 is a side elevation of a spool embodying my invention.

Fig. 4 is a longitudinal section of the same, taken on the line 4—4 of Fig. 3, and partly broken away.

Fig. 5 is a plan view of an exemplifying blank, out of which the tube is formed, partly broken away.

Fig. 6 is a similar view of a modification of the same, partly broken away.

Fig. 7 is a cross-section of the spool and winding spindle, taken on the line 7—7 of Fig. 2, and partly broken away.

Fig. 8 is a similar cross-section of a modification of the joint in the tube, partly broken away.

Fig. 9 is a similar cross-section of a further modification of the joint in the tube, partly broken away.

Fig. 10 is a side elevation of the winding spindle, partly broken away, and having the tube of my improved spool in position thereon.

Fig. 11 is a side elevation of the same, with the head of the spool in place, and showing the beginning portion of the thread being wound about the spool, and partly broken away.

Fig. 12 is a similar view, partly broken away, and showing additional windings of the thread on the spool; and

Fig. 13 is a side elevation showing a partially used spool of thread embodying my improved device and exemplifying its use with a sewing machine, in which the spool is used in upright position.

My improved device is shown as formed out of a thin, preferably resilient sheet, preferably of metal, of which terneplate or tin coated sheet iron, or non-corrosive metal, of a thickness of approximately .010 to .015 inch may be cited as

an example, as preferable for use in constructing the spools herein shown and described, although it will be understood that the material, its size, thickness and resilience may be changed 5 to make it best adaptable for the use to which my invention may be put.

The sheet is exemplified as a blank 21, of the length of the desired tube, or the tube may be made out of a strip of indefinite length, formed 10 and cut into desired lengths.

Preferably one of the longitudinal margins of the blank is provided with slots 22 located desirable distances apart and of sufficient width to receive the opposite longitudinal margin of the 15 blank. The bottoms 23 of the slots form shoulders, and the opposite longitudinal margin of the blank forms shoulders 24, which coact with the bottoms of the slots for limiting contraction in cross-sectional direction of the tube to the 20 minimum diameter desired. This opposite longitudinal margin of the blank is preferably continuous.

If desired, both longitudinal margins may be provided with slots 25, as shown in Fig. 6, the 25 end walls of the slots in one margin being received between the end walls of the slots in the other margin in forming the blank into a tube.

The blank is bent into substantially cylindrical form, the margin 26 being received in the slots 30 22. The portions 27, 28 of the blank between the slots form tongues which are alternately located at opposite sides of the opposite longitudinal margin of the blank, to form a lap joint 29 for the tube extending lengthwise of the tube. 35 Pressure perpendicular to the joint is exerted on the joint for arranging the joint as nearly as possible in the plane of the cylinder of the tube, whereby inwardly extending pockets 31 and outwardly extending pockets 32 are formed in the 40 margins 26 of the tube for receiving the tongues 27, 28, or the pockets may be formed in the blank or strip prior to bending the tube, as may be desired. The formation of this tube may be accomplished by suitable means.

45 The tube is preferably so formed that the outer surface thereof is cylindrical, as exemplified in Fig. 7. If desired, the inner surface of the tube may be made flush, as shown in Fig. 8, depending on the use to which the tube may be put, or, 50 if desired, the joint may be so formed that the contacting surfaces of the laps in the joint of the tube may be in the median plane of the cylinder of the tube, as exemplified in Fig. 9, as may be desired.

55 One end of the tube is provided with a radially outwardly extending shoulder extending about the tube, exemplified as an annular flange 34, shown outwardly tapering or frusto-conical.

The head may be formed of material similar 60 to that of the tube. It is exemplified as tapering outwardly, radially and lengthwise, with relation to the tube, and is shown of frusto-conical form, and its inclination may be such as is desired. It is provided with a central hole 41, the 65 wall 42 of which is received about the tube and forms a shoulder which coacts with the shoulder 34 on the tube to prevent endwise separation between the tube and the head in a given direction lengthwise of the tube to assemble the spool.

70 The head is preferably provided with an annular shoulder, shown formed as a flange 43, which extends about the outer edge of the head and forms a trough 44 or gutter.

The inner wall of the trough is preferably 75 formed by a flange 45 extending lengthwise of

the spool at an angle to the frusto-conical surface of the head. The angle between said frusto-conical surface and the flange 45 usually defines the diameter of the body of thread on the spool. The flange 43 is bent reversely at the outer edge 5 of the flange 45. These flanges and trough strengthen the head.

The tube is preferably provided with radially outwardly extending protuberances 46 which form inner shoulders adjacent to its flanged end, but spaced from the flange 34 by a space 47, in which the wall 42 of the head of the spool is received when the tube and head are in connected relation. The protuberances 46 form inner shoulders and the flange 34 of the flanged end forms an outer shoulder, the space 47 being located between said inner shoulders and said outer shoulder and has the wall 42 of the central hole 41 in the head located as a shoulder therein. The tube is sufficiently resilient to permit the wall 42 to be snapped over the shoulders or protuberances 46 when assembling the tube and the head by lengthwise movement between the tube and the head, the outer end flange or shoulder 34 of the tube and the wall 42 of the 25 hole 41 arresting lengthwise movement between the tube and the head in one direction. Opposite lengthwise movement between the tube and the head is permitted so that there may be passage endwise of the tube between the inner 30 shoulders or protuberances 46 and the wall 42 of the hole in the head in opposite direction, for separation between the tube and the head when disassembling the parts of the spool.

The end walls of the slots 22 and the end walls 35 of the pockets 31 located at the outside of the tube, form shoulders for the inner layers of the thread 48 when the thread is being wound upon the spool, so as to arrest slippage of the inner layers of the thread lengthwise of the spool when 40 the thread is being wound upon the spool, and the spool may be provided with outwardly extending protuberances 49 for aiding in arresting slippage of the inner layers of the thread lengthwise of the spool. The protuberances may be 45 impressed in the material. These latter protuberances may extend throughout a desirable portion of the length of the tube, being especially useful near the head end of the same, and they 50 may be arranged at desirable distances apart and about the tube.

When the blank or strip is formed into a tube by lapping its opposite margins, it is preferably so formed that there is a slight space 50 between its coacting shoulders 23, 24, in order that the tube may be slightly contracted to bring said shoulders into coaction, and the tube is preferably yieldable cross-sectionally throughout its length, so as to contract or distend the same cross-sectionally, and such contraction or distending may take place selectively at the respective ends of the tube to aid in assembling the tube and its head.

The wall 42 of the head is also preferably slightly resilient so as to be yieldable to permit 65 it to be slipped over the protuberances in the tube, and when slipped over the protuberances 46, this wall is located and held firmly between said last-named protuberances and the flange 34, that is, between the inner passable shoulders 46 70 and the outer impassable shoulder 34 at the inner end of the tube.

While such wall 42 and the shoulders or protuberances 46 are being moved endwise to pass each other in assembling the same, the flanged 75

end of the tube is momentarily compressed to cause contact between the lateral shoulders 23, 24 next adjacent thereto as fulcrums and to contract the flanged end of the tube into a cross-sectional dimension smaller than the cross-sectional dimension of the wall 42 to permit said wall and the inner shoulders or protuberances 46 to pass each other, so that said wall may be received as a shoulder between said inner shoulders 10 or protuberances and the outer shoulder or flange 34 at the end of the tube, the balance of thelapping margins of the tube shifting outwardly and momentarily enlarging the spaces 50 between the shoulders 23, 24 at the outer end of the tube, the 15 said margins teetering upon the innermost lateral shoulders 23, 24 as fulcrums.

The tube and head resile partially to normal relation when such assembly has been accomplished, permitted by the resiliency of the material out of which the tube and preferably the head are formed. When winding of the thread upon the tube is begun, the outer end of the tube is contracted, and its inner end expanded by teetering on said fulcrums to cause clamping between 25 the inner end of the tube and the wall of the hole in the head to lock the tube and head together rotatively, aided by the frictional contact of the thread therewith.

Illustrating the use of my improved spool, I 30 have shown the same in connection with a portion of a suitable winding machine in Figs. 1, 2, 7, 10, 11 and 12, and in connection with a suitable sewing machine in Fig. 13.

When the spool is being wound it is usually 35 placed horizontal, and when the wound spool is handled or used it is usually placed vertical.

The exemplified winding machine includes a suitable frame 55, in which a suitable winding spindle 56 is journaled. Suitable means, not 40 shown, are provided for rotating the winding spindle and also for moving the same endwise to control the locus of the spool with relation to the range of movement of the thread arm of the winding machine. Such a usual thread arm is shown 45 at 57 and is provided with a thread slot 58, through which the thread 48 being wound is guided. The thread arm is oscillated to move its thread end in opposite directions lengthwise of the spool during rotation of the spool, thereby 50 laying the thread about the spool in coarse spiral paths in a range from the head of the spool to a suitable distance inward of the outer end of its tube.

During such winding operation the spindle with 55 its spool is gradually moved endwise by suitable mechanism, not shown, so that the range or locus of laying of the thread, as the diameter of the body of the thread increases, continues to extend progressively to equal extent from portions nearer 60 the base of the conical head, in order to form the outer end of the winding frusto-conical, similar to the frusto-conical form of the head of the spool.

The speed of rotation of the spindle may decrease as the diameter of the spool increases, controlled by suitable means in the winding machine, not herein shown, or the tension of the thread 65 may be varied, to insure uniform laying of the thread.

Considerable tension is applied to the thread 70 as the spool is being wound, and great pressure is exerted upon the head of the spool by the thread, tending to move the head outwardly, but this outward movement of the head is resisted by the substantial outer shoulder or flange 34 at the head 75 end of the tube.

The end of the thread to be wound about the spool is in practice looped, as shown at 59 in Fig. 11, about the head end of the tube, and the winding machine is set in operation for winding the thread upon the spool. The first windings of the thread upon the spool contract the tube cross-sectionally for coaction between the laterally presented shoulders 23, 24, these shoulders limiting such contraction to the definite diameter desired, it being understood that the thread is wound 10 under considerable tension.

The outer periphery of the spindle is polygonal in cross-section, being shown as of hexagon form having corners or angles 60, which are preferably 15 slightly rounded to conform to the inner cross-sectional contour of the spool.

In my improved device the base ends 28' of the tongues 28 (Fig. 7) and the marginal edges of the inwardly extending portions of the margin 26 (Fig. 4) form shoulders extending lengthwise of the tube at the inside of the tube which are contacted by one of the shoulders 60 extending lengthwise on the spindle and formed by the cross-sectional form of the spindle. This forms a positive driving connection between the spindle and the spool. In the forms shown in Figs. 8 and 9 frictional contact between the spool and the spindle, accentuated by the clamping force of the thread in contracting the tube about the spindle 25 may form the driving connection between the 30 spindle and the spool.

A collar 65 is located about the spindle and is held to the spindle in suitable position lengthwise of the spindle to accommodate the length of the spool being wound. It is shown clamped in suitable position to the spindle by a set screw 66. One end of this collar is preferably of frusto-conical form for providing a locating face 67 co-acting with the inner face of the frusto-conical head of the spool. This collar has a rabbet 68 40 at its inner end adjacent to the spindle for accommodating the flange 34 at the inner end of the tube of the spool.

This endwise movement of the spindle and spool during the winding operation causes the outer 45 end of the body of thread wound on the spool to be of frusto-conical form to avoid unraveling of the thread at said end.

The body of the thread when wound on the spool is usually of a diameter corresponding to 50 an outer end portion of the frusto-conical head, depending on the length and thickness of the thread wound on the spool, the outer diameter of the body of wound thread on the spool being preferably within the cylindrical plane of the 55 groove 44.

During use of the thread, for instance, on a power sewing machine, the spool is usually located upon an upright stem 69 extending from a frame 70 of the sewing machine, or suitably 60 located near the sewing machine about a similar stem on a usual thread stand. The thread is usually unwound endwise of the spool, being guided beyond the free end of the spool. It sometimes happens during such use, that the 65 thread will become slack adjacent to the spool and form a depending loop 71. This loop in my improved device is lodged in the gutter 44, and is thereby prevented from dropping below the lower end of the spool. In older constructions, in the absence of my improved device, such loops of thread have lodged under the spool, the thread also becoming wound around the stem over which the spool is placed, with the result that when tension was again applied to the 70 75

thread, that the thread either became torn or the spool was moved endwise off of the stem, resulting in loss and damage, which are prevented by my improved device.

5 In operation, tubes of suitable lengths as, for instance, three inches, four inches, five inches, etc., are selected for the particular job of winding, depending on the diameter of the thread and the lengths of thread to be wound upon the 10 spool. The selected tube is placed over the winding spindle, as in Fig. 10, and the head is slipped endwise about the spindle and the tube and pressed endwise with relation to the tube, the flange of which is seated in the rabbet 68 15 of the collar 65, as shown in Fig. 2. Such endwise pressure of the head moves the wall 42 of the central hole in the head beyond the inner shoulders or protuberances 46. The resilience of the tube and of such wall permits this to be 20 done for lodging said wall between said inner shoulders or protuberances 46 and the outer shoulder or flange 34, and thereby assembles the tube and its head.

The head end of the tube will be slightly contracted in diameter, and this head end may also flex into the spaces formed by the flat portions of the hexagon spindle, to permit the passage of the wall 42 past the protuberances 49 and the inner shoulders or protuberances 46 on the tube 30 during such contraction in diameter. The flanged end of the tube may also be flexed by contact of the lateral shoulders 23, 24, proximate to the flange, so as to act as fulcrums upon which the outer end of the tube will be momentarily 35 flexed to increase its cross-sectional diameter, the tube flexing back partially upon positioning of the wall 42 between the inner shoulders or protuberances 46 and the outer shoulder or flange 34, as hereinbefore explained. The selected tube and the base may also be assembled before the same are placed on the spindle.

When the winding of the thread is begun, the 40 end of the thread is looped about the head end of the tube of the spool, as shown at 59 in Fig. 11, the thread being wound in coarse spirals about the tube, as exemplified in Fig. 11. The inner 45 layers of the thread are held endwise of the tube by shoulders 72, 73, respectively formed by the outer ends of the tongues and the end 50 walls of the outer pockets, and the protuberances 49, the outer layers being held endwise of the tube by contact with preceding spirals of the 55 thread, succeeding spirals being arranged in different angular relations to each other about the spool.

The direction of rotation of the spindle during winding is exemplified by the arrow 74 in Figs. 1, 7, 11 and 12, one of the shoulders 69 of the 60 spindle (Fig. 7) contacting shoulders 28 at the bases of the inwardly extending tongues 28 and the marginal edges of the inwardly extending portions of the margin 26 in the tube for forming 65 positive driving connection between the spindle and the spool. The spool is preferably wound during rotation of the spindle clockwise when viewed from the outer end of the spool thereon.

During use of the thread, for instance, in a power sewing machine, the thread is unwound in opposite direction to its direction of winding, 70 with the result that the inner layers of the thread readily release from the shoulders 72, 73, which they may have contacted during the winding of the same. In unwinding the thread the inner 75 layers of the thread are prevented from being

caught under the tongues and the corners of the outer ends of the walls of the slots.

Various tubes of different lengths may be assembled with any of the heads, so that a minimum number of tubes of respectively different lengths, depending on the demand for such respective different lengths, and a minimum number of heads for all of said lengths, may be carried in stock by the manufacturer winding the thread, resulting in great economy. 10

Spools, according to my invention, employ material of minimum thickness, are light in weight, and occupy little space, and the wound spools of thread employing by improved spools occupy a minimum of space and are of minimum weight, thereby saving in space and weight in storage and shipment without reduction in lengths or thicknesses of threads on the respective spools. This results in material economy, especially when it is considered that when employing previous constructions of spools a spool having one pound in weight of thread of a given length thereon, as a four inch spool, usually weighed between two and a half and three ounces, whereas in my improved device the corresponding spool of thread weighs only one ounce. My improved device is further economical, in that it requires smaller packages for enclosing the same, and in that the same is less bulky for shipment, storage and use, and in that the spool is stronger and resists endwise pressure of the thread thereon to substantially greater extent than spools heretofore in general use. 25

The wood, paper or fibre spools heretofore in general use, on account of their absorption of moisture, have been subject to mildew which was communicated to the thread wound thereon, resulting in great loss, the absorption of moisture also rendering the spools soft or mushy, both before and after being wound, resulting in ready 40 crushing and breakage of the spools, all avoided in my improved device. 35

My improved device further presents an inner surface 75 at the end of the spool on which suitable indicia, denoting size, quality and other characteristics of the thread thereon, and advertising matter, may be readily placed and be of sufficient size to be readily read, and the protruding end 76 of the spool beyond the thread 50 may also be employed for placing suitable indicia thereon. 45

In my improved device, further, the tubes may if desired be nested one within the other, as by momentarily spreading the tubes, and the heads may also be nested one within the other, or stacked, for saving space in storage and in shipment, resulting in great economy when compared with spools as heretofore made. 55

My improved form of tubing also permits the 60 lapping margins of the joints to be shifted outwardly with relation to each other for accommodating the tubing to the different diameters of different articles to be placed therein, as for instance mandrels of different diameters, while at the same time contraction of the tube beyond a desired minimum diameter during maintenance of lapped relation of its margins is limited by coaction between the shoulders lateral of the respective lapping margins of the tube. 65

The resilient tube also continuously acts expansively upon the material as the body of thread, located about the same. 70

The parts of my improved tube may be readily disassembled and reassembled for use and after 75

use may be nested and packed in compact arrangement for reshipment and reuse.

Having thus fully described my invention, what I claim as new and desire to secure by Letters 5 Patent, is:

1. A single head take-apart spool comprising a tube and a head respectively having wound material engaging portions thereon coacting to hold the wound material on the spool, said tube and 10 said head being assembled and separable by endwise movements between said tube and said head in manner that said wound material engaging portions are moved past one another in opposite directions lengthwise of said tube, and said tube and 15 said head provided with normally coacting permanent relatively releasable shoulders extending transversely to the axis of said tube and coacting and relatively impassable upon assembling of said tube and said head by relative 20 longitudinal movement therebetween in one of said directions and for disassembling thereof as a separate tube and a separate head by relative longitudinal movement therebetween in the opposite of said directions.
2. A single head take-apart spool comprising a tube having a material engaging portion for wound material and inner and outer longitudinally arranged shoulders at one of its ends and a head having a hole in which said tube is located with the wall of said hole forming an intermediate shoulder normally located between said first-named shoulders, there being resilient radial yielding between said intermediate shoulder and said inner shoulder to locate said intermediate shoulder by endwise passage along said material engaging portion endwise on said tube past said inner shoulder upon said outer shoulder to definitely relatively locate said head in outward direction on said tube, with said intermediate shoulder coacting releasably with said outer shoulder for endwise releasing movement in opposite direction between said head and said tube along said material engaging portion.
3. A tube having longitudinally extending lapping margins including a margin having tongues formed by narrow slots in said margin, in which slots the opposite one of said margins is located, said slots being substantially equal in width to the thickness of said opposite one of said margins, 45 said opposite one of said margins having bends therein lengthwise of said tube and extending alternately in opposite directions transverse to said opposite one of said margins to form pockets alternately at the respective sides of said opposite 50 one of said margins, with alternate ones of said tongues located at opposite sides of said opposite one of said margins in alternate ones of said pockets, and said bends and the respective walls of said slots coacting as shoulders to hold said 55 respective margins in longitudinally extending relation.
4. A tube having longitudinally extending lapping margins including a margin having tongues formed by narrow slots in said margin, in which 60 slots the opposite one of said margins is located, said slots being substantially equal in width to the thickness of said opposite one of said margins, said opposite one of said margins having bends therein lengthwise of said tube and extending alternately in opposite directions transverse to said opposite one of said margins to form pockets alternately at the respective sides of said opposite 65 one of said margins, with alternate ones of said tongues located at opposite sides of said 70 margins in longitudinally extending relation.
5. A single head spool comprising a tube having a material winding portion and a head having a material winding portion, said head provided with an opening in which one end of said tube is located, said tube having a material winding portion and said head having a material winding end presented toward said material winding portion, arranged for having the material wound on said material winding portion and against said material winding end, said tube formed out of resilient sheet material the longitudinally extending margins of which are lapped along said material winding portion and laterally shiftable after completion of said tube relatively to said material winding end and provided with coacting lateral shoulders adjacent to the head end 25 of said tube which act as fulcrums on which the laps of said margins are tilted by radial compression of the outer end of said tube to contract the outer end of said tube at one side of said fulcrums whereby to expand said head end of 30 said tube at the other side of said fulcrums to clamp said head end of said tube and said head together.
6. A single head spool comprising a tube and a thread retaining head, said head provided with an opening in which one end of said tube is located, said tube having a material winding portion and said head having a material winding end presented toward said material winding portion, arranged for having the material wound on said material winding portion having the material wound thereon against said material winding end, said tube formed out of resilient sheet material the longitudinally extending margins of which are lapped and laterally shiftable after 40 formation of said tube and provided with coacting lateral shoulders adjacent to the head end of said tube which act as fulcrums, the head end of said tube provided with an inner protuberance and an outer protuberance having a space therebetween longitudinal of said tube at one side of said fulcrums, said head and said tube arranged to be assembled by lengthwise movement between said head and said tube with said material winding portion and said material winding end 45 having such lengthwise movement one along the other past said fulcrums toward said protuberances whilst said tube is in said opening whereby to cause teetering of said margins on said fulcrums during passage between said inner protuberance and said wall to locate said wall in said space, said outer protuberance arresting such assemblng movement, and said margins provided with coacting shoulders at the other side of said fulcrums to limit contraction of the tube 50 at said other side of said fulcrums in order to maintain said wall in said space.
7. A single head spool comprising a tube having a material winding portion extending lengthwise thereof on its outer periphery and a head 55 having a material winding end presented toward said material winding portion, said head provided with an opening, said tube and said head being relatively resilient radially of the axis of said tube, said head and said tube arranged for 60

- relative movement therebetween lengthwise of said tube whereby there is movement between said material supporting portion and said material winding end along said material winding portion, the head end of said tube provided with a shoulder to arrest such longitudinal movement between said tube and said head in one direction to hold said tube and said head together, said tube provided with a protuberance at its head end spaced inwardly from said shoulder longitudinally of said tube, the wall of said opening arranged to be located in the space between said protuberance and said shoulder by such movement in the same direction between said tube and said wall, said protuberance and said wall being relatively radially yieldable for passage between said wall and said protuberance due to resilient yielding between said protuberance and said wall.
8. A take-apart single head spool comprising a completed tube and a completed head, said head provided with an opening in which one end of said tube is located, said tube formed of resilient sheet material the longitudinally extending margins of which are lapped and relatively laterally yieldable in the completed tube, said margins provided with coacting shoulders to limit contraction of said tube, the head end of said tube provided with a shoulder coacting with said head beyond one end of said coacting shoulders to arrest movement between said tube lengthwise of said tube and said head in one direction to hold said tube and said head together, and said tube and said head constructed to have movement between them lengthwise of said head in the opposite direction for separation between said tube and said head, whereby the completed tube is releasably associated with the completed head to form the spool.
9. A single head spool for use in upright position, the head whereof is provided with a thread receiving gutter at its outer portion extending radially outward from the head to receive thread loosely hanging from said spool when in upright position, the inner wall of said gutter extending lengthwise of the axis of said spool and substantially defining the diameter of the body of thread wound on said spool.
10. An endwise partable single head spool comprising a tube and a head for having material wound about said tube with outward end pressure against said head, said tube and said head provided with means to resist said outward end pressure for relatively locating said tube and said head, said means being oppositely separable to constitute said head and said tube releasable and separable with relation to each other in endwise direction opposite to the direction of said outward end pressure when said spool is devoid of material.
11. An endwise partable spool comprising a tube having a material winding portion and a head about said tube at the end of said material winding portion for having the material wound thereagainst, said material exerting outward end pressure against said head when the material is wound on said spool, said tube and said head provided with means to resist said outward end pressure for relatively locating said tube and said head, said means being oppositely separable to constitute said head releasable from said tube by endwise movement of said head along said material winding portion of said spool.
12. An endwise take-apart single head spool comprising a completed tube normally expansible
- in cross-section and having a material supporting portion and a head having a material supporting end and a hole for said tube, endwise holding means between one end of said tube and said head to hold said tube and said head together at said one end against pressure of a body of material on said material supporting portion bearing against said material supporting end, and said head movable along said material supporting portion during absence of said material for assembling and disassembling said spool.
13. In a single head take-apart spool, the combination of a tube and a frusto-conical head having a central hole, said tube having an outer annular flange and an inner radially outwardly extending shoulder spaced inwardly from said flange to form a longitudinal space therebetween on said tube, said head and said tube relatively movable lengthwise of said tube in both endwise directions whereby passage between said inner shoulder and the wall of said hole in both said directions takes place to locate said wall in said longitudinal space and to remove said wall therefrom for respectively assembling and disassembling the spool, and said wall coacting with said flange to limit longitudinal movement in one of said directions lengthwise of said tube between said tube and said head to releasably assemble the spool.
14. In a single head take-apart spool, the combination of a tube having lapping longitudinal margins provided with coacting lateral shoulders on which said margins are arranged to be teetered, and a frusto-conical head having a central hole, said tube having an outer annular end flange and an inner radially outwardly extending shoulder spaced inwardly from said flange to form a longitudinal space therebetween on said tube, said head and said tube relatively movable lengthwise of said tube in both endwise directions whereby passage between said inner shoulder and the wall of said hole in both said directions takes place by such teetering to locate said wall in said longitudinal space and to remove said wall therefrom for respectively assembling and disassembling the spool, and said wall coacting with said flange to limit longitudinal movement in one of said directions lengthwise of said tube between said tube and said head to assemble the spool.
15. In a single head take-apart spool, the combination of a tube having lapping longitudinal margins provided with coacting lateral shoulders on which said margins are arranged to be teetered, and a frusto-conical head having a central hole whose wall is resilient, said tube having a permanent outer annular end flange to form an outer end shoulder, said tube having an inner radially outwardly extending shoulder radially flexible and spaced inwardly from said flange to form a longitudinal space on said tube between said last-named shoulders, said head and said tube relatively movable lengthwise of said tube in both endwise directions whereby passage between said inner shoulder and said wall in both said directions takes place upon yielding of such resilient wall and such teetering of said longitudinal margins on said lateral shoulders to locate said wall in said longitudinal space and to remove said wall therefrom for respectively assembling and disassembling the spool, and said wall coacting with said flange to limit longitudinal movement in one of said directions lengthwise of said tube between said tube and said head to assemble the spool.

16. A single head take-apart spool comprising a tube having longitudinally arranged inner and outer shoulders at one of its ends and a head having a central hole in which said tube is normally located, the wall of said hole normally forming an intermediate shoulder longitudinally between said first-named shoulders, said tube and said head being relatively longitudinally

movable in opposite directions with said inner shoulder and said intermediate shoulder relatively passable for assembling and disassembling the spool, and said intermediate shoulder and said outer shoulder relatively impassable in assembling direction for releasably holding said tube and said head in assembled relation.

EDWARD T. ALLAN.
